UNITED STATES PATENT OFFICE.

JOSEPH L. EIRICH, OF BROOKLYN, NEW YORK.

TRAIN-STOPPING DEVICE.

1,089,191.

Specification of Letters Patent.

Patented Mar. 3, 1914.

Application filed June 14, 1913. Serial No. 773,722.

To all whom it may concern:

Be it known that I, JOSEPH L. EIRICH, residing at Brooklyn, in the county of Kings and State of New York, have invented new and useful Improvements in Train-Stopping Devices, of which the following is a specification.

My invention relates to railway signals, and pertains more particularly to apparatus for automatically applying the brakes of railway cars or trains.

The object of my invention is to produce an attachment coupled with the air-brake pipes of railway trains adapted to be tripped by an adjustable plate adjacent to the track for releasing the air and applying the brakes to the cars.

Another object thereof is to produce an adjustable trip operated by electricity and controlled by the adjustment of the semaphore signal of ordinary design, adapted to intercept and apply the brakes on a train or locomotive should said train disregard the danger signal in the semaphore.

A further object thereof is to produce electrically controlled and operated means for raising and lowering the tripping mechanism by and in accord with the operation of the semaphore signal, and a still further object of my invention is to produce a more simple, cheap and efficient device of said character than has heretofore been accomplished.

To these ends my invention includes the combination and arrangement of component parts to be hereinafter described and more particularly pointed out in the claims.

In the accompanying drawings, in which like reference characters indicate similar parts, Figure 1 is a perspective view of a locomotive and semaphore signal equipped with my device; Fig. 2 is a side view of my brake trip with the case removed; Fig. 3 is a top plan view of the same; Fig. 4 is an opposite side view of the same; Fig. 5 is a transverse view thereof; Fig. 6 is a side view of the air-brake trigger; Fig. 7 is a longitudinal sectional view of the air-brake cap and operating trigger, and Fig. 8 is a detail view of the removable cap for the air-brake pipes. Fig. 9 is a diagrammatical view of the electrical currents and the con-

tacting points by which the circuits are made and broken.

Referring, now to the drawings, 1 indicates the air pipes on the locomotive by which the air-brakes are controlled, and 2 designates a flexible extension coupled therewith and leading to the plate 3 carried on the side of the locomotive in the frame 4, 60 and on which it is vertically adjustable by the rack 5 and pinion wheel 6. As shown in the drawings, said plate is provided with an orifice 7 and a projecting nipple 8 surrounding the orifice on which is secured the cap 9 and depending trigger by which the cap is turned to disengage same from its position thereon. The nipple 8 is provided with an annular flange thereon having a plurality of projecting lugs 10 while the cap 70 is provided with a plurality of notches 11 in its edge adapted to register with the lugs when the trigger 12 depending from the cap is pressed backward out of vertical alignment. Within the orifice 7 in the plate 3 and nipple 8 is seated a coil spring 8 seated at its inner end on the spider 14 and pressing outwardly on the inner face of the cap 9 as shown in Fig. 7 of the drawings, and adapted, when the trigger and cap are turned to 80 register the lugs 10 and notches 11, to force the cap off of the nipple and admit the air into the train pipe to apply the automatic brakes of the train.

The trigger 12, is operated in the manner 85 described by a tripping plate controlled and actuated by the adjustment of semaphore signal device 14 placed adjacent thereto, the operating parts of which are electrically coupled with the actuating mechanism of the 90 tripping plate. As the semaphore mechanism is of ordinary construction, it will not be particularly described, except as to the parts employed in the operation of the tripping plate, as hereinafter referred to, and 95 I shall now proceed to describe the means for raising and lowering the tripping plate to engage or avoid the trigger 12.

The plate 13, as shown, is covered in a suitable case, and located adjacent a railway track. Said plate is adjustable vertically and carried in the guide frames 14, mounted on the base 15, and is provided with a rack 16 on each of its vertical edges adapt-

ed to project through slots in the frames 14 14' to engage the pinion wheels by which it is raised. Said pinion wheels are oppositely rotated by the electric motor A which is 5 energized by an electrical circuit leading thereinto, and controlled by the action of the operating mechanism of the semaphore signal hereinafter described, and the operation is communicated to the pinions through 10 a series of intermediate gears and wheels as follows: The drive pinion 17 on the motor armature meshes with the large gear 18 mounted on the motorbox, which meshes with the driven gear 19 mounted on vertically adjustable bearings 20 carried on the base 15 of the tripping plate frame. On the opposite end of the shaft 21 on which the gear 19 is carried is rigidly mounted the gear wheel 22 which meshes with the gear wheel 23 of equal size therewith, and mounted on the shaft 24, and said gear 23 meshes with gear 23' of similar size mounted on shaft 23''. Rigidly mounted on the shafts 21 and 24 are the sprocket wheels 25 and 26 respectively which actuate the chains 27 and 28 respectively and which pass over the sprocket wheels 29 and 30 mounted on the same shafts on which are rigidly carried the pinions 31 and 31' and by which said pinions are operated in opposite directions to raise the tripping plate 13.

The electric circuit by which the motor A is energized, flows through a circuit breaker C mounted on the frame 14, which is normally closed, but the tripping plate 13 is provided with a lug D so positioned that it will engage the circuit breaker C and disengage the contacting faces thus stopping the action of the motor. The tripping plate, however, is held in raised position by the spring actuated latch E which engages a keeper E' just prior to the breaking of the circuit and the completion of the raising of the plate. Said latch is connected with an armature F adapted to be actuated by the magnet G which is energized by a circuit which is controlled by the adjustment of the semaphore signal operating mechanism to safety position, which thereby releases the latch and permits 50 the tripping plate to drop by gravity out of the path of the trigger 12.

It will be apparent from the foregoing description, and as illustrated in Fig. 9 of the drawings, that the operation of my device is 55 accomplished by two electrical circuits, which are supplied by the line wires H and I leading from any suitable source of supply. Both circuits are primarily controlled by the contact plate 33 carried on the operating arm 34 of the semaphore. When said arm is positioned at danger, as shown in dotted lines, it contacts the plate 33 with the contact points 35 and 36, which com-

pletes the circuit through wires 37 and 38 and the circuit breaker C to the motor A. 65 Upon the completion of the upward travel of the tripping plate, the circuit breaker C is disconnected to stop the operation and the waste of electricity.

When the arm is raised to safety, as shown 70 in full lines in Fig. 9, the motor A energizing circuit is broken, and as said arm travels upward the plate 33 contacts for a brief period with the points 39' and 40' of the wires 39 and 40 which energizes the electro-magnets G to release the latch and permit the plate 13 to drop, after which, on the completion of the travel of the arm, said circuit is broken by the dis-connecting of the contact 39' from the plate 33. 80

It will be understood that the semaphore mechanism is operated by an electric circuit controlled by the approach and departure of a locomotive or train within the adjacent blocks.

In operation, the cap and trigger 12 are placed on the nipple 8 to close the end of the fixture carried on the air-brake system on the locomotive as shown in Figs. 1, 6 and 7 of the drawings. If the semaphore signal is set at safety the tripping plate 13 is depressed and the trigger will pass over same, but if the semaphore is positioned at danger, the electro-motor A is energized by the electric-circuits hereinbefore described, and the tripping plate is elevated to such position that should the approaching train attempt to pass the danger signal, the plate will engage the trigger and turn it and the cap sufficiently to register the notches and lugs on the cap and nipple, whereupon the spring S forces the cap off and admits air to the brake pipes and sets the brakes to bring the train to a stop. 95 100 105

Having thus described my invention, what I claim as new, and desire to be secured by Letters Patent, is:—

1. In a train stopping device, the combination with a semaphore signal mechanism having an oscillating arm and electric contacts thereon, of a vertically adjustable track obstacle, an electric motor geared with said obstacle for raising same, a latch for holding said obstacle in raised position, an electro-magnet for releasing said latch, an electric circuit connected with the contacts on the semaphore arm when in lowered position for actuating the motor to raise the obstacle, and an electric circuit connected with the contacts on said semaphore arm when in raised position to actuate said latch-operating electro-magnet to permit said obstacle to lower, substantially as described. 110 115 120 125

2. In a train stopping device, the combination with a semaphore signal mechanism having an oscillating arm and electric con-

tacts thereon, of a vertically adjustable track obstacle, an electric motor geared with said obstacle for raising same, an electric circuit connected with the contacts on the semaphore arm adapted to energize the motor for raising the obstacle, a circuit breaker adjacent said obstacle, and means carried on the

obstacle for operating said circuit breaker when the obstacle attains the desired height, substantially as described.

JOSEPH L. EIRICH.
